AIR BRUSH HOLDER OR SIMILAR ARTICLE

Dallas R. Bottcher, 911 Cobblestone Drive,
Lincoln, Nebr. 68510

Filed Dec. 12, 1974, Ser. No. 532,254

Term of patent 14 years

Int. Cl. D23—99

U.S. Cl. D23—167

FIG. 1

FIG. 2

FIG. 3

FIG. 5

FIG. 4

FIG. 6

FIG. 8**FIG. 7****FIG. 8****FIG. 10****FIG. 11****FIG. 12**FIG. 1 is a perspective view of an air brush holder or similar article showing my new design;

FIG. 2 is a side elevational view of the embodiment of FIG. 1;

FIG. 3 is a plan view of the embodiment of FIG. 1;

FIG. 4 is a bottom view of the embodiment of FIG. 1;

FIG. 5 is a fragmentary perspective view of another embodiment of the invention showing the only difference over the embodiment of FIG. 1;

FIG. 6 is a fragmentary perspective view of still another embodiment of the invention showing the only difference over the embodiment of FIG. 1;

FIG. 7 is a perspective view of still another embodiment of the invention;

FIG. 8 is a side elevational view of the embodiment of FIG. 7;

FIG. 9 is a plan view of the embodiment of FIG. 7;

FIG. 10 is a perspective view of still another embodiment of the invention;

FIG. 11 is a side elevational view of the embodiment of FIG. 10; and

FIG. 12 is a front elevational view of the embodiment of FIG. 10.

I claim:

The ornamental design for an air brush holder or similar article, substantially as shown and described.
